(57) **CLAIM**

The ornamental design for a trim component, as shown and
described.

DESCRIPTION

FIG. 1 is a cross-sectional view of a first embodiment of a
trim component, taken along line 1-1 in FIG. 5.

FIG. 2 is a perspective view of the trim component of FIG.
1.

FIG. 3 is a perspective view of the trim component of FIG.
1.

FIG. 4 is a perspective view of the trim component of FIG.
1.

FIG. 5 is a front elevation view of the trim component of
FIG. 1, which indicates a cross-section line 1-1.

FIG. 6 is a cross-sectional view of a second embodiment of
a trim component, taken along line 6-6 in FIG. 9.

FIG. 7 is a perspective view of the trim component of FIG.
6.

FIG. 8 is a perspective view of the trim component of FIG.
6.

FIG. 9 is a front elevation view of the trim component of
FIG. 6, which indicates a cross-section line 6-6.

FIG. 10 is a side elevation view of the trim component of
FIG. 6.

FIG. 11 is a rear elevation view of the trim component of
FIG. 6.

FIG. 12 is a perspective view of the trim component of FIG.
6.

FIG. 13 is a perspective view of the trim component of FIG.
6; and,

FIG. 14 is a rear elevation view of the trim component of
FIG. 6.

The trim component is shown with a symbolic break in its
length. The appearance of any portion of the trim component
between the break lines forms no part of the claimed design.
The broken lines in the drawings illustrate portions of the
trim component that form no part of the claimed design.
